(57) **CLAIM**

The ornamental design for an eyelash curler handle as shown and described.

DESCRIPTION

FIG. 1 is a front, right side, top perspective view of an eyelash curler handle showing our new design;

FIG. 2 is a rear elevational view thereof;

FIG. 3 is a top view thereof;

FIG. 4 is a bottom view thereof; and,

FIG. 5 is a left side view, the right side view being a mirror image thereof.

The singled-dotted broken lines at the ends of the solid line portions define the bounds of the claimed design and form no part thereof. The dashed broken lines illustrate environmental structure and form no part of the claimed design.
